SUCTION CLEANER

Bernard C. Becker, deceased, late of Canton, Ohio,
by Bernice E. Becker, executrix, York, Pa., as-
signor to The Hoover Company, North Canton,
Ohio, a corporation of Ohio

Application December 29, 1938, Serial No. 248,298

13 Claims. (CL. 306—13)

The present invention relates to suction cleaners and particularly to new and improved handle control mechanism in a suction cleaner. More specifically the invention comprises an improved handle position control in a suction cleaner which is characterized in that the handle is locked in position when bodily moved with respect to the cleaner.

It is an object of the present invention to provide a new and improved suction cleaner. It is another object to provide new and improved handle control means in a suction cleaner. It is another object to provide a handle control mechanism that is operated merely by manipulating the handle. A further object is to provide a handle control mechanism that is operated by the weight of the cleaner to lock the handle in storage position and prevent relative movement between the cleaner casing and the handle. Further objects and advantages of the invention will be apparent upon referring to the following specification and claims and the attached drawings, wherein:

Figure 1 is a side elevation of a suction cleaner embodying the present invention;

Figure 2 is a perspective view of one embodiment of the invention showing the handle locked in storage position;

Figure 3 is a view showing the handle in a low operating position;

Figure 4 is a section corresponding substantially to the line 4—4 of Figure 3;

Figure 5 is a sectional view of the handle in storage position;

Figure 6 is a sectional view of another embodiment of the invention showing the handle in storage position;

Figure 7 is a section along the line 7—7 of Figure 6, and

Figure 8 is a view of the handle in a low operating position.

One embodiment of the invention shown in Figures 2 through 5 is employed in the suction cleaner illustrated in Figure 1 comprising a main casing 10 having a nozzle 11 and an unshown fan chamber communicating with an exhaust passageway 12, the rear end of which is provided with a vertical flange 13 to which is removably secured a dust bag 14, which is supported at its upper end to a handle 15 pivotally mounted on the casing 10. The casing 10 supports an unshown motor enclosed in the motor housing 16, and the motor operates an unshown fan to create suction and draw dirt-laden air from the surface being cleaned into the nozzle 11, the un-

shown fan chamber, and exhausts the dirt-laden air into the dirt filtering bag 14. The cleaner is supported on front and rear wheels 17 and 18 respectively.

5 The cleaner is propelled over the surface covering by means of the handle 15 removably clamped in a rectangular handle socket 20 which is formed with integral flat side walls 21, 21 a front wall 22 and a rear wall 23. The handle socket 20 is rigidly mounted on an oval-shaped sleeve 24 extending through the socket side walls 21, the major axis of the oval sleeve extending longitudinally of the cleaner handle. The oval sleeve 24 is loosely disposed about a pivot pin 25 having its opposite ends supported in spaced handle brackets 26, 26 each provided with an offset portion 27 rigidly mounted on the cleaner casing above the exhaust passageway 12. The oval opening in the sleeve 24 permits pivotal and bodily movement of the handle with respect to the pivot pin 25 and the casing 10.

Segment means are provided along the central longitudinal axis of the handle socket 20 and includes a segment plate 28 journaled on a bushing 19 rigidly supported on the oval sleeve 24, and the plate 28 is provided along its forward edge with recesses 29, 30 and 31 defined by stops 32, 33 and 34 to form three ranges of handle position. The segment plate 28 has a downwardly extending tongue 35 which is loosely disposed in a socket 36 formed in the upper wall of the casing 10 to permit vertical movement of the plate 28 when the latter is moved bodily with the handle socket 20 with respect to the pivot pin 25 and the casing 10, as shown in Figure 5.

40 Cooperating with the segment means are handle control roller detent means which comprise an elongated rectangularly shaped detent ball casing 37 which extends through the side walls 40 of the handle socket 20 and is provided at its opposite ends with cylindrical projections 38 each having a semi-cylindrical portion 39. The detent ball casing is additionally rigidly supported in the handle socket 20 by a pair of arms 40 each having one end embracing the circular projections 38 and the opposite end rigidly carried by the oval sleeve 24. A slot 41 is provided transversely through three walls of the casing 37 and spans the segment plate 28. Loosely disposed in 45 the ball casing 37 is a pair of detent balls 42 which are retained in the casing by means of a pair of plugs 43 each having a cylindrical section 44 extending beyond the extreme ends of the ball casing 37. The detent balls 42 are normally urged into engagement with each other by means

of laminated leaf springs 45, 45 each having one end arranged about the plug projections 44 and the opposite end rigidly secured to the oval sleeve 24. In the foregoing construction when the handle is in the low operating position shown in Figure 3, the detent balls are in engagement and ride along the cam surface 29 and when the handle is moved to a higher operating position the detent balls are separated by the stop 33 against the force exerted by the leaf springs 45, whereby the handle will be free to move into a higher operating position.

In order to prevent relative bodily movement between the pivot pin 25 and the handle socket 20 means are provided to rigidly position the handle with respect to the pivot pin and comprises a member 46 having a bottom wall 47 secured to the upper wall of the exhaust passageway 12, a back wall 48 attached to the exhaust flange 13 and a pair of upstanding side walls 49 equally spaced from the segment plate 28. The side walls 49 are provided with forwardly extending arms 50, 50 each having an arcuate cam surface 51 which extends substantially from the segment stop 34 upwardly and forwardly to the stop 32. The arcuate arms 50 are provided with a rectangular slot 52 opposite the segment recess 31 which is adapted to receive the detent means or detent ball casing 37 to hold the handle in storage position shown in Figure 2. When the handle is moved through the operating ranges between the detent stops 32 and 34 one wall 53 of the detent casing 37 slides along the cam surfaces 51 of the arms 50 to force the handle socket forwardly as shown in Figure 3 to thereby prevent relative bodily movement between the handle socket 20 and the pivot pin 25. When the handle is in storage position the detent casing is arranged opposite the storage locking slots 52 and enters the latter when the weight is removed from the casing 10 by exerting an upward lift on the handle to cause the latter and the detent casing 37 to bodily move with respect to the pivot pin 25.

In order to counterbalance the weight of the cleaner handle 15 a pair of springs 54 are provided and have one end secured to lugs on the handle brackets 27 and their opposite ends secured to pins 56, 56 secured to the side walls of the handle socket at a point forwardly of the handle pivotal axis 25.

In operation, assume the handle is in the low operating position shown in Figure 3, the detent balls 42 disposed in the recess 29, and the detent casing 37 in engagement with the arcuate surfaces 51 so as to prevent bodily movement between the handle control means and the pivotal axis 25. If it is desired to move the handle to its intermediate operating position the operator merely rotates the handle upwardly and the detent balls 42 are separated against the force of the springs 45 as they approach the stop 33 to permit the handle to move past the latter, and thereafter the springs 45 move the detent balls 42 toward each other to permit movement of the handle in the operating range between stops 32 and 34 into the recess 30. If it is desired to move the handle to storage position the operator merely rotates the handle upwardly until the detent balls 42 enter the storage recess 31.

When the handle is in storage position the major axis of the oval sleeve 24 is disposed vertically. If it is desired to bodily lift the cleaner to another position the operator exerts an upward force on the cleaner handle to lift the lat-

ter, which causes the cleaner handle 15, handle control means and the oval sleeve 24 to move bodily upwardly with respect to the pivot pin 25 and casing 10. Since the detent casing 37 is in register with the locking slots 52 in the arms 50, the upward movement of the handle causes the detent casing 37 to enter the locking slots 52 and due to the rectangular contour of the locking detent means 37, the latter will be locked in the slots 52, to prevent the cleaner nozzle from rotating downwardly with respect to the handle. When the operator places the cleaner on the floor the handle socket 20, segment 28 and detent casing 37 will move downwardly with respect to the pivot pin 25 and casing 10, the detent casing 37 moving downwardly out of engagement with the locking slots 52 whereby the detent balls 42 yieldably hold the handle in storage position.

Another embodiment of the invention is shown in Figures 6 to 8 and comprises the handle 15 disposed in the handle socket 20 which is rigidly attached to an elongated cylindrical sleeve 60 journaled about a pivot pin 61 mounted for bodily movement in elongated oval openings 62 in a pair of spaced arms 63 of a handle bracket 64 having a back wall 55 secured to the exhaust flange 13 of the cleaner casing 10.

The oval openings 62 have their major axis arranged vertically in the handle brackets, whereby the pivot pin 61 may be moved vertically therein. The rectangular detent ball casing 37 is disposed transversely of the handle socket walls 21 and is additionally secured to the socket by means of a pair of arms 40 each having one end attached to the projecting ends 38 of the detent casing 37 and the opposite end rigidly secured to the cylindrical sleeve 60. The detent balls 42 are loosely accommodated in the detent casing 37 and are retained in the latter by means of the plugs 43 and the leaf springs 45 rigidly secured to the bearing sleeve 60 and journaled about the plugs 43 to urge the detent balls 42 into engagement with each other. The segment means 28 is arranged along the longitudinal central axis of the handle socket and is supported about the bushing 19 concentric with the sleeve 60. The tongue 35 at the lower end of the segment plate 28 is slidably disposed in the socket 36 formed in the upper wall of the exhaust passageway 12.

Disposed within the handle socket 20 and rigidly secured to the side walls 21 of the latter is a pair of arms 65 each having one end journaled about the bushing 19 and having a forwardly extending portion 66 to which is secured a pair of pins 67 which extend through the side walls 21 of the handle socket. Secured to the extreme ends of the pins 67 are a pair of springs 68 which have their opposite ends secured to lugs 69 provided on the handle bracket 64, the springs acting to counterbalance the weight of the cleaner handle.

In order to provide a rigid positive locking mechanism to prevent the casing from rotating with respect to the handle when the latter is in storage position and the cleaner is lifted off-the-floor, the arms 65 are each provided with a locking edge 70 which is adapted to engage a stop 71 at the upper extreme end of the back wall 55 of the handle bracket when the handle is bodily moved vertically with respect to the cleaner casing.

In operation if it is desired to move the handle from low operating position shown in Figure 8 to a higher operating position, the operator rotates the handle upwardly, the segment stop 33 caus-

ing the detent balls 42 to separate against the force exerted by the leaf springs 45 which thereafter urge the balls 42 into the segment recess 30 to permit free movement of the handle in the selected operating range. If it is desired to move the handle to storage position the operator merely rotates the handle upwardly to storage position shown in Fig. 6, and the detent balls 42 will be in register with the storage recess 31 to hold the handle in storage position.

In this position the handle and pivot pin 61 are free to move upwardly in the oval openings 62 in the handle bracket 64, since the major axis of the oval openings are at all times disposed vertically. If it is desired to lift the cleaner from the floor the operator exerts an upward force on the handle which causes the pivot pin 61 and the mechanism supported thereby to bodily move vertically in the oval openings 62 with respect to the casing 10. Upward movement of the handle causes segment 28, the detent means and the locking arms 65 to also move upwardly with respect to the casing 10, the locking edges 70 of the locking arms 65 moving to a point opposite the stops 71. When the cleaner is completely lifted off the floor the weight of the cleaner being forward of the pivotal axis 61 causes the nozzle of the cleaner to rotate downwardly. Such downward tilting causes the locking stops 70 and 71 to abut each other to rigidly lock the casing 10 with respect to the cleaner handle 15. When the cleaner is again placed on the floor the handle 15, segment 28, detent means 37 and the locking stop 70 will move bodily with respect to the pivot pin 61 downwardly toward the casing to disengage the locking means 10 and 71 and permit normal operation of the handle control means and movement of the handle with respect to the casing.

It is to be understood that the protection herein applied for is not confined to the particular combinations of features or elements set out in the following claims. Protection is herein applied for, for any one or more of the features or elements referred to in the following claims, or described in the foregoing specifications or shown in the accompanying drawings, either independently or in combination.

What is claimed is:

1. In an ambulatory machine, a body, a handle, means constructed and arranged to support said handle pivotally on said body and to permit bodily movement of said handle with respect to said body, locking segment means carried by said body, locking detent means carried by said supporting means and bodily moveable with said handle, said locking detent means being bodily actuated to engage said locking segment means upon bodily movement of said handle to a predetermined position to lock said handle in said position.

2. In an ambulatory machine, a body, bracket means on said body, a pivot pin carried by said bracket means, a handle, means for supporting said handle, said supporting means being pivotally mounted about said pivot pin and arranged with respect to the latter for bodily movement with respect thereto, and coacting locking means carried by said supporting means and said body, said coacting locking means being actuated into locking engagement upon said bodily movement of said handle with respect to said pivot pin to a predetermined position to lock said handle in said position.

3. In an ambulatory machine, a body, bracket means on said body, a pivot pin carried by said

5 bracket means, a handle, means for supporting said handle, said supporting means having a lost-motion connection with said pivot pin for pivotal and bodily movement of said handle with respect to said pivot pin, handle control means for holding said handle in different positions when the latter is pivoted about said pivot pin, means for preventing said bodily movement of said handle when the latter is moved to said different positions, and coacting locking means carried by said supporting means and said body, said coacting locking means being actuated into locking engagement upon bodily movement of said handle with respect to said pivot pin to a predetermined position to lock said handle in said latter position.

4. In an ambulatory machine, a body, bracket means on said body, a pivot pin carried by said bracket means, a handle, means for supporting said handle, said supporting means having a lost-motion connection with said pivot pin for pivotal and bodily movement of said handle with respect to said pivot pin, handle control means including segment and detent means for holding said handle in different positions when the latter is pivoted about said pivot pin, locking detent means, cam means engageable with said locking detent means for preventing said bodily movement of said handle when the latter is pivoted to said different positions, and locking segment means actuated into locking engagement with said locking detent means upon said bodily movement of said handle with respect to said pivot pin to another position to lock said handle in said another position.

5. In an ambulatory machine, a body, bracket means on said body, a pivot pin carried by said bracket means and mounted thereon for a bodily movement with respect thereto, a handle, means for pivotally supporting said handle on said pivot pin, and coacting locking means carried by said supporting means and said body, said coacting locking means being actuated into locking engagement upon bodily movement of said handle and pivot pin to a predetermined position to lock said handle in said position.

6. In an ambulatory machine, a body, a handle, bracket means on said body and having an elongated opening with its major axis substantially parallel to the storage position of said handle, a pivot pin carried in said opening for bodily movement along its major axis, means for pivotally supporting said handle on said pivot pin, and coacting locking means carried by said supporting means and said body, said coacting locking means being actuated into locking engagement upon bodily movement of said handle and pivot pin to said storage position to lock said handle in said position.

60 7. In an ambulatory machine, a body, a handle pivotally mounted on said body, segment means and detent means carried by said handle and comprising a detent casing carried by said handle, a pair of detent balls carried by said casing and disposed on opposite sides of said segment means, spring means for urging said detent balls into engagement, said detent balls coacting with said segment means upon movement of said handle to hold the latter in the desired position.

70 8. In a suction cleaner, a body, supporting means on said body constructed and arranged to support pivotally said handle during normal cleaning operation and including means to permit bodily movement of said handle with respect to

said body, handle control means for resistingly maintaining said handle in different operative positions upon said pivotal movement of said handle with respect to said body, and coacting locking means carried by said supporting means and said body actuated upon said bodily movement of said handle with respect to said body for rigidly locking said handle with respect to said body.

9. In an ambulatory machine, a body, a handle, means pivotally and slidably mounting said handle on said body, and coacting locking means having a part carried by said body and another part movable with said handle, said coacting locking means being actuated by translatory movement of said handle on said slidable mounting into locking engagement to lock said handle against pivotal movement on said body.

10. In an ambulatory machine, a body, means on said body defining elongated openings, a handle pivotally and slidably mounted in said elongated openings, and coacting locking means having a part carried by said body and another part movable with said handle, said coacting locking means being actuated by translatory movement of said handle in said elongated openings into locking engagement to lock said handle against pivotal movement on said body.

11. In a suction cleaner, a casing, a handle pivoted on said casing, handle control means for resistingly maintaining said handle in different operating positions relative to said casing and including a displaceable element, and locking

means automatically operable upon lifting the cleaner from the floor engageable with said control means to lock said element against displacement positively and so lock said handle with respect to said casing.

12. In a suction cleaner, a casing, a handle pivoted on said casing, handle control means for resistingly maintaining said handle in different operating positions relative to said casing, and means pivotally mounted on said casing for locking said control means to positively lock said handle with respect to said cleaner, said locking means being actuated by the influence of gravity when said cleaner is lifted from its supporting surface.

13. In a suction cleaner, a casing containing cleaner mechanism, a handle pivoted on said casing toward the rear of the latter rearwardly of the center of gravity thereof, said casing of its weight rotating downwardly and forwardly with respect to said handle when the cleaner is lifted off its supporting surface by said handle, and coacting locking means on said handle and casing for locking said handle rigidly with respect to said casing and including an element normally held in inoperative position by cleaner weight with the cleaner on the floor, said element being adapted to move to operative position upon the lifting of the cleaner.
